UNITED STATES PATENT OFFICE.

LEWIS CRAVEN ORD, OF MONTREAL, QUEBEC, CANADA, ASSIGNOR TO RICHARD W. BURNETT, OF MONTREAL, CANADA.

HEATING SYSTEM.

1,131,947.

Specification of Letters Patent.

Patented Mar. 16, 1915.

Application filed April 12, 1912. Serial No. 690,433.

To all whom it may concern:

Be it known that I, LEWIS CRAVEN ORD, of the city of Montreal, in the Province of Quebec, Dominion of Canada, have invented 5 certain new and useful Improvements in Heating Systems, of which the following is a specification.

My invention relates particularly to the 10 automatic control of steam heating systems, but certain of its features in the broader conception thereof are applicable to other uses.

The invention has for its principal object 15 to utilize the heat conducting medium itself to automatically control the heat radiated, and, at the same time, maintain a clear passage through the radiator for the flow of the medium by drawing from the radiator at any one of a number of different points demarcating limitations of its heat radiating surface to cause the portion of the medium thus drawn to act upon and operate the means controlling the supply of the medium.

A further object is to provide as articles 25 of commerce devices for adjusting the points at which the heat conducting medium is drawn from the radiator, and for thermostatically controlling the supply to the radiator.

30 The invention may be said, broadly, to consist of adjustable means effecting a communication between one of a plurality of different points in a radiator and means for controlling the same; and, specifically speaking, it consists of the construction, combination, and particular arrangement of 35 parts hereinafter described and pointed out in the claims.

For full comprehension, however, of my 40 invention, reference must be had to the accompanying drawings forming a part of this specification, in which similar reference characters indicate the same parts, and wherein:

45 Figure 1 is a front elevation of a part of a railway car heating system containing my invention; Fig. 2 is a fragmentary side elevation showing the heating coils and car floor in section. Fig. 3 is a plan view of 50 the structure shown in Figs. 1 and 2; Figs. 4, 5 and 7 are detail front elevation, side elevation and sectional view, respectively, of the adjustable device for effecting the connection with the radiator at any one of a 55 number of different points; Fig. 6 is a trans-

verse vertical sectional view taken on line A A Fig. 5; Fig. 8 illustrates the development of the valve of the device shown in Figs. 4 to 7 inclusive; Fig. 9 is a plan view of the thermostatic controller. Fig. 10 is a 60 side elevation thereof; Fig. 11 is an elevation of the front side of the controller partly in sectional view; Fig. 12 is a sectional view of the controller taken on line D D Fig. 11; Fig. 13 is a sectional view taken on line F F 65 Fig. 12; Fig. 14 is a sectional view taken on line G G Fig. 12; and Fig. 15 is a sectional view taken on line E E.

I have illustrated, as the preferred embodiment, my invention applied to a railway car heating system, a seat being indicated at a.

The heating coil of the car consists of 70 four pipes b, c, d, e, the lowermost being divided and two branches, f and g, taken 75 therefrom beneath one of the seat.

A vertical section i, is set into the coil adjacent to the branch g and is divided into a series of four chambers j, k, l, m, each effecting communication between the portions 80 of the pipes on the opposite side thereof. Within this section a vertical tubular valve chamber o is cast having a series of ports p, q, r and s therein which communicate with the respective chambers j, k, l, m, such 85 ports being in staggered arrangement. A tubular valve t, within this valve chamber, has a series of ports u, v, w, x in the same horizontal planes and corresponding in capacity with the ports in the valve chamber 90 and the lower end of this valve communicates with a port y in the base of the section and has a pipe 2 of relatively small bore 95 extending therefrom to a thermostatic valve operating device to be presently further al- 95 luded to. The upper end of the valve has a rigid collar 3 by which it is supported on the top side of the valve chamber and a tapped projecting sleeve 4 is plugged by the

external screw threaded hub 5 of a miter 100 gear 6 fixed in place by a pin 7, the valve being rotatably held against vertical displacement by a boss 8 upon the center of the interior of a screw cap 9 having an external hexagonal boss 10, and screwed into the 105 tapped upper end of the casting. This valve is operated manually by a handle 12 fixed upon the outer end of a spindle 13 extending through a stuffing box 14 in the side of the casting and having rigidly mounted upon 110

its inner end a miter gear 15 intermeshing with the miter gear 6, the stuffing box being carried by a screw plug 16 screwed into the side of the section; the plug 16 and cap 9 being of sufficient diameter to permit the gears 15 and 6 and the valve *t*, being removed for repairs or renewals.

The thermostatic operating device consists of a casting 20 chambered as at 21 to 10 contain a diaphragm 22 having a central convex boss 23 on its outer side and on its inner side a hollow central cylindrical thimble 24, the latter working through an opening in a wall 25 and the former limited 15 against movement in an outward direction with the diaphragm by an adjusting screw 26 set by a lock nut 27. This adjusting screw is carried by a cap 28 closing one side of the chamber and having an eccentrically tapped opening 29 into which the 20 end of pipe 2 is screwed. The portion of the casting beneath the diaphragm has connected thereto a pair of concentric drip pipes 30 and 31, the former communicating 25 directly with the diaphragm chamber.

The opposite end of the casting has connected thereto an air intake pipe 33 and within the latter a steam inlet pipe 34 communicating with a port 35 terminating at 30 one side in a valve seat 36 upon which bears a steam control valve 37 operated by a handle 38 and stem 39. The valve chamber 40 in which this valve is located communicates by a passage 41 with an opening 35 in the axial line of the diaphragm thimble 24 and contains a hollow plug 43 with a square head 44 and screw threaded end 45 inserted through the casting and screwed through a wall 46 separating the passage 41 from a valve chamber 50, the end of the 40 plug 43 projecting slightly into this valve chamber and serving as a valve seat, while a portion thereof within the passage 41 has a staggered series of ports 51.

45 A steam port 48 effects a communication between this passage 41 and a chamber 49. The valve within this valve chamber is indicated at 52 and is carried by a stem 53 having a rigid collar 54 and projecting 50 through a wall 155 into the diaphragm thimble 24. The collar 54 limits the movement of the stem toward the diaphragm and affords a seat for one end of a helical spring 55 encircling the stem and the valve seat 45, the valve having a washer 57 for obvious reasons. This valve chamber is closed at its upper end by a screw cap 58 and the lower end thereof communicates with a passage 60 which in turn communicates with a 55 steam port 61 in a steam nozzle 62 arranged to direct a jet across an air chamber 63 into a delivery pipe *f* connected to the casting by a coupling 65 containing an oppositely flared mixing chamber 66 and a drain- 60 age hole 67 communicating with chamber 65

63. Air is mixed with the steam by this device. It enters from the pipe 33 by passages 75 and 78 into the chamber 63.

The nozzle is screwed into a tapped opening 80 in the casting, and extends from the 70 inner wall of the chamber 49 to a point about half way through the chamber 63. It consists of a pair of members 81 and 82, and a screw-plug 83 closes the outer end 75 of the hole. The member 81 is of conical 80 form with an extended screw-threaded base and an axial boring 84 terminating at its apex end in a diminutive bore 85. The member 82 is in the form of a frustum of wider angle than the cone 81 and encircling 85 the same near its apex and screwed into the portion of the hole 80 between the port 60 and chamber 63, while the base of the cone 81 is screwed into the portion of the hole between the ports 49 and 60. The object 85 accomplished by the nozzle is to cause steam projected from the ports 60 and 49 into chamber 63 to be enveloped in air accompanying it from the chamber 63, the enveloping air being thoroughly commingled 90 in the mixing chamber with the steam projected by the nozzle.

The handle 12 registers with graduations on a dial 166 on the frame of the seat *a* or other suitable place to indicate the relative angular position of the valve *f*. The device *per se* with its nozzle for supplying the heating fluid and ejecting air and its thermostatic controller is a feature of my invention and is applicable to other uses 95 than described.

Operation: The operation of my improved heating system is as follows: If maximum heat is desired, the handle 12, and with it the valve *t* is rotated to the position 105 necessary to cause the port *s* only to be open. Upon steam being admitted to the system by opening the valve 38, it will flow from the train-pipe 100 through the pipe 34, ports 35 and 41, plug 43, valve chamber 110 50, port 60, nozzle member 82, and accompanied by air as above mentioned, through the mixing-chamber 66 to pipe *f* and thence through the entire coil, pipe *g*, port 190, to the main drip pipe 31. Simultaneously 115 steam will flow (see Figs. 14 and 15) from port 35 to valve chamber 40 and thence by passage 41 and ports 48, 49 and 84 to the diminutive jet perforation 85. If steam above a given maximum is flowing through the pipe *g* a portion of it will pass through port *s* and pipe 2 to the diaphragm chamber, and cause the diaphragm to close the valve 52 thus shutting off the steam supply 120 to port 60 which is the main steam supply 125 to the system. The diminutive jet 85 is controlled solely by the valve 38 and consequently remains active until the valve 38 is closed, the effect being that a continuous small supply of steam flows through the 130

system thus preventing condensation therein without perceptibly heating the coil. Another advantage is that there is no interference with the clear passage above described through the system. To reduce the effectiveness of the radiator the valve *t* is turned to cause the ports *r* and *w* to register, and a portion of the heat conducting mixture to enter the valve and pass through the port *y*, pipe 2 and opening 29 to the diaphragm chamber 21 and expand the diaphragm, thus closing the valve 52 and shutting off the main steam supply to the radiator. Immediately the temperature within the radiator falls the diaphragm will resume its normal position and valve 52 will be opened again by its spring 55. In order to still further reduce the heat radiating surface, the valve *t* may be turned to effect a connection between any other port in this valve and the corresponding level in the radiator and the same action will result; and obviously an increase in effective radiating surface may be obtained by a reverse operation.

What I claim is as follows:

1. The combination with a divided heat radiating coil, means for supplying a heat conducting medium thereto, and means controlling the supply, of an oblong hollow section of rectangular cross section extending across the coil uniting the divided portions thereof and containing distinct compartments effecting communication between the respective pipes of the coil, and a tubular valve chamber disposed longitudinally and having a rectilinear series of ports communicating with the respective compartments and a port in the end of the said hollow section communicating with one end of the valve chamber; a tubular valve within the valve chamber and having a spiral series of ports adapted to register with the respective ports of the said valve chamber; means for adjustably rotating the valve; and a fluid conductor leading from the port communicating with the end of the valve chamber to the controlling means.

2. The combination with a divided heat radiating coil, means for supplying a heat conducting medium thereto, and means controlling the supply, of an oblong hollow section of rectangular cross section extending across the coil uniting the divided portions thereof and containing distinct compartments effecting communication between the respective pipes of the coil, and a tubular valve chamber disposed longitudinally and having a rectilinear series of ports communicating with the respective compartments and a port in said hollow section communicating with the valve chamber at one end thereof; a tubular valve within the valve chamber and having a spiral series of ports adapted to register with

the respective ports of the said valve chamber; manual means for adjustably rotating the valve; and a fluid conductor leading from the end port of the hollow section to the controlling means.

3. The combination with a divided heat radiating coil, means for supplying a heat conducting medium thereto, and means controlling the supply, of an oblong hollow section of rectangular cross section extending across the coil uniting the divided portions thereof and containing distinct compartments effecting communication between the respective pipes of the coil, and a tubular valve chamber disposed longitudinally and having a rectilinear series of ports communicating with the respective compartments and a port in said hollow section communicating with one end of the valve chamber; a tubular valve within the valve chamber and having a staggered series of ports adapted to register with the respective ports of the said valve chamber; means for adjustably rotating the valve consisting of an intermeshing pair of miter-gears and manually operative means for the gears, one of the gears being mounted rigidly upon the valve; and a fluid conductor leading from the port of the hollow section communicating with the end of the valve casing to the controlling means.

4. The combination with a divided heat radiating coil, of an oblong hollow section of rectangular cross section containing distinct compartments with coupling apertures in opposite sides, couplings uniting the said coupling apertures to the separated parts of the coil; and a tubular valve chamber disposed longitudinally and having a rectilinear series of ports communicating with the respective compartments and a port in said hollow section communicating with one end of the valve chamber; a tubular valve within the valve chamber and having a staggered series of ports in the radial planes of the respective ports of the said valve chamber, and means for adjustably rotating the valve.

5. The combination with a divided heat radiating coil, of an oblong hollow section of rectangular cross section containing distinct compartments with coupling apertures in opposite sides, couplings uniting the said coupling apertures to the separated parts of the coil, and a tubular valve chamber disposed longitudinally and having a rectilinear series of ports communicating with the respective compartments and a port in said hollow section communicating with one end of the valve chamber; a tubular valve within the valve chamber and having a staggered series of ports adapted to register with the respective ports of the said valve chamber and means for adjustably rotating the valve consisting of an intermeshing pair of miter-gears, and manually operating means for

the gears, one of the gears being mounted rigidly upon the valve.

6. The combination with a heat radiator, of a thermostatically controlled means for supplying a heating medium thereto consisting of a steam passageway including an outer and an inner valve chamber, an air passageway, said member being provided with a bore which extends from the steam passageway to said air passageway; steam injecting means having independent communication with each of said chambers and arranged in said bore so as to direct steam across said air passageway, a valve adapted 10 to control the flow of steam through said outer chamber, a valve in said inner chamber for controlling the flow of steam through said chamber, a diaphragm chamber formed with a drip outlet, a diaphragm 15 in the diaphragm chamber, a fluid conductor connecting the radiator to the diaphragm chamber, and means operatively connecting the diaphragm with the valve in said inner chamber so as to regulate the passage of 20 steam from said chamber to said steam injecting means.

7. The combination with a heat radiator, of a thermostatically controlled means for supplying a heating medium thereto consisting of a member containing a steam passage including a pair of valve chambers at the outer and inner ends thereof, an air chamber and an air port communicating therewith, said member being provided with a bore extending across and communicating with the air chamber and inner end of the steam passage, means closing one end of the bore, a diaphragm chamber having a drip outlet, and a steam port communicating with the 30 diaphragm chamber; a pair of valves in the 35

outer and inner valve chamber respectively of the steam passage and independently controlling the steam supply to and from the steam passage, manual means operatively connected to the valve in the outer valve 45 member, a diaphragm in the diaphragm chamber; means operatively connecting the diaphragm to the inner valve; a branch steam port communicating with the first mentioned steam passage at a point between 50 the valve chambers and also communicating with the said bore; a pair of nozzles one encircling the other, and both nozzles being located in the said bore, one of the nozzles being fed from the inner valve chamber of the 55 steam passage and the other nozzle being fed from the branch steam port; a steam conductor connecting the radiator to the steam port of the diaphragm chamber; a mixing chamber communicating with the air chamber and nozzles; and a conductor for the mixture of air and steam and extending from the mixing chamber to the radiator.

8. In a heating system, the combination with a radiator provided with a steam inlet 60 and an air inlet, of a thermostatic device adapted to govern the flow of steam through said steam inlet, and a tubular valve provided with a plurality of ports adapted by oscillation of a single member to put said 65 thermostatic device into communication with any one only of a number of different portions of said radiator.

In testimony whereof I have signed my name to this specification in the presence of 70 two witnesses.

LEWIS CRAVEN ORD.
